US0D1089448S

(12) **United States Design Patent** (10) **Patent No.:** **US D1,089,448 S**
(45) **Date of Patent:** **** Aug. 19, 2025**

(54) **MODEL VEHICLE BUMPER ASSEMBLY**

(71) Applicant: **TRAXXAS, L.P.**, McKinney, TX (US)

(72) Inventors: **Adam Cole Ewing**, McKinney, TX (US); **Otto Karl Allmendinger**, Rowlett, TX (US); **Caleb Hix**, McKinney, TX (US); **Noah House**, Sachse, TX (US); **Trent Collins**, McKinney, TX (US)

(73) Assignee: **TRAXXAS, L.P.**, McKinney, TX (US)

(**) Term: **15 Years**

(21) Appl. No.: **29/894,963**

(22) Filed: **Jun. 15, 2023**

(51) LOC (15) Cl. **21-01**

(52) U.S. Cl.

USPC **D21/561**

(58) **Field of Classification Search**

(57) **CLAIM**

The ornamental design for a model vehicle bumper assembly as shown and described.

DESCRIPTION

FIG. 1 is an upper, left, front perspective view of a model vehicle bumper assembly showing our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is an upper plan view thereof;

FIG. 7 is a lower plan view thereof;

FIG. 8 is a lower, left, front perspective view thereof;

FIG. 9 is an upper, right, rear perspective view thereof; and, FIG. 10 is a lower, right, rear perspective view of the model vehicle bumper assembly.

In the drawings, the broken lines illustrate portions of the model vehicle bumper assembly that form no part of the claimed design.

1 Claim, 7 Drawing Sheets
